UNITED STATES PATENT OFFICE.

EMIL UTZ AND THEODOR SPRICK, OF ODESSA, RUSSIA.

CAR-STARTER.

SPECIFICATION forming part of Letters Patent No. 272,358, dated February 13, 1883.

Application filed December 16, 1882. (No model.)

To all whom it may concern:

Be it known that we, EMIL UTZ and THEODOR SPRICK, subjects of the Emperor of Russia and Emperor of Austria, respectively, and 5 residents of Odessa, in the Empire of Russia, have invented a certain new and useful Improvement in Car-Starters, of which the following is a specification.

The object of this invention is to facilitate 10 the starting of tram-cars.

With reference to the accompanying drawings, Figure 1 is a longitudinal section; Fig. 2, a view below the car-floor, and Fig. 3 a transverse section of parts of a tram-car fitted 15 with our apparatus. Fig. 4 is a side view, partly in section, showing a modified form of apparatus; and Fig. 5 shows an entire tram-car fitted with our arrangements.

On each of the two axles of the two pairs of 20 wheels is keyed a ratchet-wheel, *a*. On each side of the ratchet-wheel *a* the levers *b b*, carrying between them the pawl *c*, are pivoted. The pawl *c* is provided with the weight *e*, having the tendency to raise it away from the 25 ratchet-wheel. The levers *b b* are connected by the rods *h g* with the draw-bar. The rod *g* is provided with the adjustable nut *h*, which, when the rod is drawn forward, presses against the helical spring *m*, and thus limits the forward motion of the said rod. By altering the 30 position of the nut *h*, the length of the draft of the rod *g* may be adjusted. The joint of the rods *g k* is hung to a cross-beam of the car by means of the link *i*. The pawl *c* is connected 35 by a cord or chain, *l*, with the treadle *f* on the platform of the car.

The action of this apparatus is as follows: When the horse or horses drawing the car are stopped the yoke goes back, and pushing back 40 the rods *g k* the levers *b b* also fall back, so that they will have the position shown in Fig. 1. Before starting, the driver presses his foot

on the treadle *f*, thus drawing forward the cord or chain *l*, and raises the weighted end of the pawl *c* and brings its other end into gear with 45 the ratchet-wheel *a*. On then starting the car the rods *g k* pull forward the levers *b b* and with them the pawl *c*, thus moving the ratchet-wheel keyed to the axle and consequently also moving the car-wheels.

It is evident that the levers *b b* may be connected to the rod *g* by means of a chain, as shown in Fig. 4, instead of the rod *k*.

In order to keep out of action the starting arrangement attached to the hinder pair of 55 wheels, the hind treadle, *f*, may be fixed by any suitable locking arrangement, *p*, as indicated in Fig. 5.

It is evident that the ratchet-wheel *a* may be made in two pieces, in order to facilitate attaching it to the axle, and that a single lever *b*, instead of a pair of levers, may be used.

We claim—

1. In a car-starter, the combination of a ratchet-wheel upon the axle of the car, a pivoted lever upon the axle, rods connecting the pivoted lever to the draw-bar, and a retractile spring upon said rods with a weighted pawl pivoted to the ratchet-lever and normally out of contact with the ratchet, said pawl being 60 connected by cords or other flexible connection to a foot-treadle, whereby the depression of the treadle will bring the pawl into action, substantially as described.

2. The adjustable nut *h* on the rod *g*, in combination with the helical spring *m*, for the purpose described.

In testimony whereof we have affixed our signatures in presence of two witnesses.

EMIL UTZ.
THEODOR SPRICK.

Witnesses:

HENRY C. YOUNG,
GEORG SCHWARTZ.
